UNITED STATES PATENT OFFICE

JOHN W. OMEY, OF DETROIT, MICHIGAN, ASSIGNOR TO PACKARD MOTOR CAR COMPANY, OF DETROIT, MICHIGAN, A CORPORATION OF MICHIGAN

LAPPING AND GRINDING DEVICE

Application filed November 2, 1927. Serial No. 230,431.

This invention relates to lapping and grinding devices and more particularly to grinding devices for finishing cylindrical apertures.

It has been the practice heretofore to provide a plurality of radially adjustable abrading members for lapping or grinding cylinders. The abrading members usually comprise grinding stones or bars of lapping metal used with an abrading compound and are generally mounted on supports which in the past have not proven entirely satisfactory because the abrading members have not been supported with sufficient rigidity to prevent warping, bending and other injury thereto, and the supports are also found lacking in adequate means for mounting and demounting the abrading members.

In some instances the abrading members are mounted on supports in lead or other soft metal cast as binders to secure the abrading members in position. In such cases the matter of replacement and repair causes considerable annoyance and unnecessary delay, since in dismounting the abrading members it becomes necessary to melt the metallic binders in which they are set, and in mounting to position the abrading members in the supports and cast the binders. By this method the supports become warped and distorted due to the constant heating thereof and are thus rendered worthless. The present invention aims to overcome these objectionable features by providing a suitable support member and a readily demountable abrading member.

An object of the invention is to provide suitable support means for abrading members for lapping or grinding cylinders.

Another object of the invention is to provide a lapping or grinding device for grinding or finishing cylinders having readily demountable abrading members.

Yet another object of the invention is to provide a lapping or grinding device for grinding or finishing cylinders having a plurality of radially adjustable supports each carrying an abrading member which may be easily and quickly removed or replaced.

A further object of the invention is to pro-

vide a lapping or grinding device for grinding cylinders comprising support members each carrying a demountable interlocking abrading member which may be easily and quickly removed or replaced.

Another object of the invention is to provide a lapping or grinding device for grinding or finishing cylinders and to construct such device so that the grinding or abrading members are supported parallel to the axis of the working head and are radially adjustable with respect thereto.

A still further object of the invention is to provide a lapping or grinding device for grinding or finishing cylinders, which is highly efficient in operation and yet of marked simplicity as a whole and in respect to each of its component parts so that its manufacture is economically facilitated both as to parts and their assembly.

Other objects of the invention will appear from the following description taken in connection with accompanying drawings, which form a part of this specification, and in which:

Figure 1 is a side elevation illustrating the abrading members in position;

Figure 2 is a vertical sectional view;

Figure 3 is a top plan view; and

Figure 4 is an enlarged detail view of one of the abrading members.

Referring by numerals to the drawings, 10 represents a working head comprising a cylindrical body having a plurality of radial bosses 11 arranged in pairs and bored normal to the axis of the head as indicated at 12, to receive arms 13 spotwelded or otherwise secured or formed upon support members 14. The arms 13 are normal to the support members 14, and accordingly, the supports are parallel to the axis of the head.

As shown, the support member 14 has a back portion 15 with parallel flanges 16, the oppositely disposed side walls of which are bevelled in opposite directions as indicated at 17 to form a dovetailed channel 18. Fitting into the channel 18 is a lapping or abrading member 19, the side faces of which are bevelled to fit snugly in the channel, and in instances where the lapping or abrading

members do not fit in the channels perfectly, gib or shims are employed and backed by the screws 20. The abrading members are further secured in position by screws 20' mounted transversely in the flanges 16 adjacent to the respective ends of the lapping or abrading members. These screws serve to clamp the flanges 16 upon the bevelled edges of the lapping or abrading members, the back portions 15 of the support members yielding sufficiently for this purpose. As shown, the screws 20' have mounted thereupon sleeves 21, which engage the respective ends of the abrading members to prevent lateral movement thereof, the sleeves being provided with lugs 22 fitting in notches 23 in the ends of the support members and bent or curved to form hooks 24 for the reception of a spring 25 adapted to retain the radial arms 11 in engagement with adjusting members mounted in the working head, to be hereinafter described.

The working head 10 is provided with a central bore 26 mounted in each end of which 25 is a cylindrical member 27 having a conical portion 28. These members are positioned in reverse with respect to each other, with their conical portions opposite the radial bores 12 to provide abutments for the arms 13. As 30 shown, the members 27 are centrally bored as indicated at 29 and one of these members is internally threaded as at 30. A shaft 31 is mounted into the threaded portion 30 in one of the members 27 and extends through 35 the bore in the other member 27 and is provided with a head 32 fitting in a recess 33, a coil spring 34 being mounted upon the shaft 31 between the members 27 to retain them in spaced relation.

40 The head 32 on the shaft 31 has pivotally connected thereto an extension shaft 35 which passes through an elongated sleeve or tubular member 36 pivotally connected to the upper end of the working head 10 by a collar 37. 45 The tubular member 36 is provided with a cap 38 through which the shaft 35 extends to provide adjustment of the members 27. As shown, the cap 38 is provided with trunnions 39 or other means may be employed for connecting the working head to suitable motor power for imparting reciprocating and rotating motion thereto.

By rotating the shaft 35 and accordingly the shaft 31 swivelled thereto, the members 55 27 will be moved away from or toward each other and in so adjusting these members the radial arms 13 on the support members 14 carrying the abrading members are moved radially inwardly or outwardly according to 60 the direction in which the shaft 31 is rotated. It is, therefore, apparent that since the abrading members may be adjusted radially, the device is adaptable for grinding cylinders of various sizes within the limits of the capacity of the device. The device is adjustable

for cylinders having the same diameter from end to end, or cylinders having a tapering or conical wall and that by reason of the particular structure of the supports for the lapping or abrading members, the matter of replacement and repairs of the lapping or abrading members may be readily and quickly accomplished, since by removing the transverse screws positioned at the respective ends of the supports the lapping or abrading members can be easily removed and replaced.

70 Although this invention has been described in connection with certain specific embodiments, the principles involved are susceptible of numerous other applications that will 80 readily occur to persons skilled in the art. The invention is therefore limited only as indicated by the scope of the appended claim.

Having described the various features of the invention, what I claim and desire to secure by Letters Patent, is:

85 A grinding device comprising a working head having central and radial bores, a sleeve connected to said working head, an adjustment mechanism in the central bore of the 90 working head, an extension shaft connected to the adjustment mechanism, said shaft extending through and beyond the sleeve and provided with means for operating the adjustment mechanism, support members 95 mounted in the radial bores of the working head, said support members having channels therein parallel to the axis of the working head, abrading members mounted in said channels, abutments in the channels at the 100 ends of the abrading members and means carried by the abutments whereby the support members are retained in adjusted position.

105 In testimony whereof I affix my signature.

JOHN W. OMEY.
